UNITED STATES PATENT OFFICE.

WILLIAM T. J. LOWE, OF BUFFALO, NEW YORK.

DESIGN FOR A TROLLING-SPOON.

SPECIFICATION forming part of Design No. 16,198, dated August 11, 1885.

Application filed June 8, 1885. Term of patent 14 years.

To all whom it may concern:

Be it known that I, WILLIAM T. J. LOWE, of Buffalo, in the county of Erie and State of New York, have originated and invented a new and useful Design for Trolling-Spoons; and I do hereby declare that the following is a full, clear, and exact description thereof, reference being had to the accompanying drawings, forming a part of this specification.

10 My invention relates to the ornamentation of the spoons used in trolling bait; and it consists in having the outer surface of such spoon provided with a portion thereof which represents a surface of repoussé or hammered work.

15 In the drawings, Figure 1 represents one style of spoon, and Fig. 2 represents a modified form.

Referring to the drawings, *a* is the spoon, which has the dividing-line *b* across its surface. This line has the form of a rounded angle, to give the spoon an artistic effect. In Fig. 1, *c* is the hammered or beaten surface,

the upper boundary of which is the line *b*, and above such line the surface of the spoon is plain and unornamented.

25 In Fig. 2 the positions of the hammered or beaten surface and the unornamented surface are simply reversed, producing substantially the same artistic effect as shown in Fig. 1.

30 I claim—

The design for a trolling-bait herein shown and described, the same consisting of a spoon upon the outer surface of which is a dividing-line having upon one side a smooth unbroken 35 surface and upon the other a representation of repoussé or hammered work.

In testimony whereof I have signed my name to this specification in the presence of two subscribing witnesses.

WILLIAM T. J. LOWE.
